UNITED STATES PATENT OFFICE.

HEINRICH SPÜHL, OF ST. GALL, ASSIGNOR OF ONE-HALF TO THE MASCHINEN-
WERKSTÄTTEN AND EISENGIESSEREI ST. GEORGEN BEI ST. GALLEN, OF
ST. GEORGEN, SWITZERLAND.

FURNITURE-SPRING-MAKING MACHINE.

SPECIFICATION forming part of Letters Patent No. 432,741, dated July 22, 1890.

Application filed June 19, 1889. Serial No. 314,848. (No model.) Patented in France January 7, 1889, No. 195,227; in Belgium January 7, 1889, No. 84,556; in England January 7, 1889, No. 262, and in Germany January 8, 1889, No. 50,312.

To all whom it may concern:

Be it known that I, HEINRICH SPÜHL, a citizen of the Federation of Switzerland, residing at St. Gall, Switzerland, have invented useful Improvements in Wire-Spring Machines, (for which I have obtained a patent in Germany, No. 50,312, dated January 8, 1889, under the name Maschinen - Werkstätten St. Georgen; in France, No. 195,227, dated January 7, 1889; in Belgium, No. 84,556, dated January 7, 1889; in England, No. 262, dated January 7, 1889, under the name Gottfried von Süsskind,) of which the following is a clear specification.

In order to make my invention more clear, I refer to the accompanying drawings, in which similar letters denote similar parts throughout the different views.

Figure 1 is a vertical section of my machine. Fig. 2 shows a horizontal section. Fig. 3 is a front view of the machine-frame, but with the shafts a' and a^3 cut away for the sake of clearness, the section-line running through the universal joints of the same in Fig. 1. Fig. 4 is a side elevation of the machine with the cog-wheels j' j^2 removed. Fig. 5 shows a top view, partly in section, of the guiding mechanism for the wire. Fig. 6 shows a side view of the same, partly in section. Fig. 7 shows an end view, partly in section, of the cutting-off mechanism and guiding-rollers. Fig. 8 shows a detail view of the cutting-off mechanism in section through the outer couplings f^3 and f^4 . Fig. 9 shows a section on line a b , Fig. 8. Fig. 10 shows a top view of Fig. 8. Fig. 11 shows a side elevation of Fig. 9.

The construction of the machine is as follows:

The driving-shaft a is journaled in the stand A. To the shaft a is fitted the fly-wheel B and friction-coupling b. The coupling b is coupled by pulling the handle b^3 , which is connected to the coupling by the rod b^2 and lever b' . There is a brake b^4 fitted to the lower end of the lever b' , which, when the coupling b is put out of gear, presses on the

rim of the fly-wheel B and stops the machine. The shaft a is fitted at its front end to the shaft a' , which carries the cutting-off mechanism by a universal joint. The upper shaft a^3 is likewise connected to the shaft a^2 by a universal joint. The shaft a^3 carries the roller c, which, together with the roller c' , feeds the wire to the machine. The shafts a and a^3 are geared together by the cog-wheels a^4 , a^5 , and a^6 , and both revolve in the same direction and with the same speed. It is necessary that they should revolve in the same direction, in order that the finished spring shall be cut off while moving. The shaft a' can be raised or lowered in the strap e by means of the screw g, for which purpose it is fitted in the sliding journals d d' , in order that the cutting-off apparatus may be adjusted to suit any diameter of spring. The upper shaft a^3 is also adjustable by the screw g' and spring g^2 , in order that wire of different thicknesses may be used. The under roller c' is driven from the shaft a^3 by the cog-wheels c^2 and c^3 . There is a small strap e' fitted inside the larger strap e, Fig. 1, to which is fastened the bearing d' at the bottom and at the top a screw, by which means the roller c can be raised in order that the wire may be brought between the feed-rollers.

The form and size of the springs are obtained by the following mechanism: On the shaft a is fitted a worm a^7 , which gears into teeth on the shaft j and revolves the same, and by means of the cog-wheels j' and j^2 and adjustable wheel j^4 on the segment j^5 , Figs. 2 and 4, the shaft j^3 is turned. The reason for placing gearing-wheel j^4 on the adjustable segment j^5 is to enable the taking out and changing of wheels j' j^2 . For instance, if a larger wheel be substituted for j' and a smaller wheel for j^2 , a shorter spring will be made, since shaft j^3 will revolve more quickly, and consequently the projection j^6 will come sooner under projection m, thus setting the cutting-off mechanism earlier in gear. To the end of this shaft j^3 is fitted the ring k on the ball-

joint k' and the washer k^3 . The ring k is clamped in any desired position by means of the nut k^2 .

According to the position of the ring k the position of the lever l is varied. This lever l turns on the pivot l^2 , and is fitted with the guide-roller l' and at the other with a roller l^3 , Fig. 5. The pivot l^2 is eccentrically fixed to a disk, which has rigidly fixed to it a hand-lever, Fig. 5, and which is in its turn pivoted to the lever l^3 . l^3 is pivoted to the machine-frame, and may be held in any desired position by means of the set-screw l^4 . The pin l^2 is mounted on the lever l^3 , in order that when l^2 stands at any point in the circle it describes the roller l^3 may be brought against the ring k by adjusting the lever l^3 ; otherwise if the pivot l^2 were standing nearly in its extreme upper position, Fig. 5, the roller l^3 would stand away from the ring k entirely. When the lever l^3 is placed in the desired position, it is clamped by means of the screw l^4 . By this means any desired pitch may be given to the wire. A slight variation in the pitch of the spring will necessarily be caused by the ring k ; but the object of the hand-lever, which may be controlled by a workman during the winding of the spring, is either to give the spring a still greater pitch in the middle, or by moving the hand-lever in the opposite direction to hinder the variation necessarily caused by the ring k . When the ring k is placed at right angles to the axis of the shaft j^3 , the lever l and the roller l' are not influenced, but they remain in the same position, and the spring will be made parallel the whole length. The more the ring k is placed from a right angle the more is the guide-roll l' moved, and the spring is made of a larger diameter at the ends than in the center. When the pivot l^2 is moved outward, the spring will have a larger diameter over all, and vice versa. It will be seen from this that the springs may be made of any size and form, according to the position of the ring k and pivot l^2 .

The springs are cut off as follows: The cutting-off mechanism is fitted to the front end of the shaft a' , and consists of the inner clutches f' and f^2 and the outer clutches or guides f^3 and f^4 , Figs. 8, 9, and 10. Both have straight stops, as seen in Fig. 9. The cutters f^5 and f^6 are brought together and the wire cut, Fig. 8. f^7 is a ring for moving the back clutch. The two back clutches f^2 and f^4 form one piece, which is fitted loosely on the shaft a' . The clutch f' is fastened to the shaft a' by the key f^9 , the end of which is formed into a spring. The clutch or guide f^3 is loose on the shaft. The whole mechanism, with the exception of f' , only makes one revolution during the cutting off of a spring.

When a spring is finished, the cam j^6 comes against the nose of the lever m , Fig. 4, and the lever and rod m' are shoved forward, and by means of the ring f^7 the back clutch

is also moved forward and is made to revolve by coming into contact with the revolving clutch f' . Thus the back clutches with f^3 are set in motion. By being set in motion the back part f^4 of the clutch, with the ring f^7 , although it has been pushed forward, is not pushed so far forward that the nose f^{10} may pass by the projection n on the bearing of the shaft. On the contrary, immediately when the back part begins to revolve the nose f^{10} is driven against the projection n , thus pressing said back part still farther forward and shoving the knives f^5 f^6 together, whereby the wire is cut off. As soon as the wire is cut off the cam j^6 passes from under the projection on the lever m and the latter falls back under the influence of the spring m^3 , pulling the coupling out of gear. In order, however, that the coupling may be brought into position with the knives upward, so that the next spring may be cut off at the next revolution of the shaft a' , which revolves continually, the spring end of the key f^9 snaps into the groove f^8 in the back part of coupling $f' f^2$ and turns it so far around until the nose f^{10} strikes against the projection n and holds thereby the back part of the coupling stationary in the position shown in Fig. 10 until the next spring is wound and cam j^6 again comes under the projection m .

The object of the spring and spindle m^2 is, that on the levers m m' being pushed forward by the cam j^6 the whole coupling shall not be forced forward, in which case if the clutches do not stand exactly in the right position the same would be liable to be broken or become notched; but the back part of the coupling will be able to spring back in the long slit in the lever m' and wait until the revolving part of the same comes into the proper position, when it will immediately spring in gear under influence of the spring and spindle m^2 , Fig. 11.

Having now particularly described and ascertained my invention, what I claim as my invention, and desire to secure by Letters Patent of the United States, is—

1. In wire-spring machines, the rotary shaft a^3 , having the roll c mounted thereon, the lever l , having at one end the roll l' and at the other the roll l^3 , the disk k , adjustably mounted on and at an angle to the shaft j^3 , and intermediate connections between the shafts j^3 and a^3 , substantially as specified.

2. The combination of the cutting-off arrangement for the springs attached to shaft a' and consisting of the inner clutches f' f^2 , outer clutches f^3 f^4 , combined spring and key f^9 , cutters f^5 f^6 , guiding-ring f^7 , back clutch f^7 f^4 , having nose f^{10} on ring f , with bearing d , having projection n , in the manner substantially as described.

3. The combination of the lever l , pivoted at l^2 , the pivot l^2 being eccentrically movable on the adjustable lever l^3 with the rollers l'

and l^3 , the latter running on the disk k , which is adjustable on the shaft j^3 by means of ball-joint k' , in the manner substantially as described.

5 4. The combination of the shafts a a^2 , connected by universal joints with the shafts a' and a^3 , respectively, the latter running in the adjustable bearings d and d' , the bearing d being adjustable in the strap e , bearing d' ad-

justable in strap e' , in the manner substantially as described.

In witness whereof I have hereunto set my hand in presence of two witnesses.

HEINRICH SPÜHL.
